(57) **CLAIM**

The ornamental design for a roadway luminaire, as shown and described.

DESCRIPTION

FIG. 1. is a top perspective view of the front of a roadway luminaire showing our new design;

FIG. 2. is a top perspective view of the rear thereof;

FIG. 3. is a bottom perspective view of the front thereof;

FIG. 4. is a bottom perspective of the rear thereof;

FIG. 5. is a top plan view thereof;

FIG. 6. is a bottom plan view thereof;

FIG. 7. is a side elevation view of the left side of the luminaire, the right side being a mirror image;

FIG. 8. is front elevation view thereof; and,

FIG. 9 is a back elevation view thereof.

The subject matter shown in broken lines is for illustrative purposes only and forms no part of the claimed design.
